ATTORNEY.

UNITED STATES PATENT OFFICE.

JACK CATHRILL, OF LOS ANGELES, CALIFORNIA.

HEADLIGHT.

Application filed August 9, 1926. Serial No. 128,184.

This invention relates to improvements in headlights and more particularly to headlights of the visor type and for use on automobiles.

5 Among the objects of my invention is to construct a headlight having a lens and a visor whose surfaces coact to produce a flood light upon the ground, of relatively great lateral distribution, in the immediate vicinity 10 of the headlight and a beam of relatively great lateral distribution whose projection is forwardly and downwardly upon the ground in advance of the headlight.

My improvements consist in the construction, arrangement and combination of lens and visor elements and surfaces as herein-after fully, clearly and concisely described, definitely pointed out in my claim and illustrated by the accompanying drawing (1 20 sheet) in which—

Fig. 1 is a longitudinal sectional elevation of a headlight constructed in accordance with my invention, showing by broken lines the downward deflection of all rays from the 25 light source.

Fig. 2 is a front elevation of the headlight showing by broken lines both downward and lateral projection of the rays by combined action of the lens and visor.

30 Fig. 3 is a rear elevation of a fragment of the lens.

Fig. 4 is a diagrammatical plan view showing the lateral deflection of the light rays as affected by the upper (visored) lens portion.

35 Fig. 5 is a diagrammatical plan view showing the lateral deflection of the light rays as affected by the lower lens portion.

Referring more specifically to the drawing 10 designates the body or barrel, of the headlight; 11 the lamp socket; 12 the incandescent lamp; 13 the parabolic reflector; 14 the lens ring, or bezel; and 15 the clamping ring, all of which are or may be of ordinary construction.

40 45 Between the reflector 13 and lens ring 14 I secure the lens A and visor B, as clearly shown in Fig. 1.

The lens is made of glass; is preferably formed by molding; its body or active area 50 is of concavo-convex shape and when in use its concave face is disposed next the light source. At a point extending diametrically across the lens above its center is a horizontal line 16 which divides the concave face into

upper and lower, or screened and direct lens 55 portions C and D, respectively.

The upper, screened portion C of the lens on its concave face is divided by ribs 17, which are relatively parallel and extend upwardly from the dividing line 16 of the lens, each rib as shown, having a substantially triangular section and forming a prism whose base is integral with the lens body and whose sides are parallelograms relatively angularly disposed, as shown in Fig. 4, and whose ends 18 at the line 16 are bevelled upwardly and toward the light source so that rays directed to the bevelled ends will be refracted upwardly through the lens, as shown in Fig. 1. The ribs 17 are curved longitudinally to follow the concave curvature of the inner face of the lens, and accordingly rays directed horizontally thereto from the reflector 13 will on passing through the lens be refracted at an upward inclination, as well 75 as laterally.

The lower, direct portion D of the lens on its concave face is divided by ribs 19, 20 and 21, whose surfaces are curved as shown in Fig. 5 and of which the rib 19, which is on the median line of the lens, extends downwardly from the dividing line 16 (see Fig. 2), the ribs 20, at the right, as viewed from the front incline downwardly and toward the left and the ribs 21, at the left, as viewed from the front, incline downwardly and toward the right.

The visor B is made of opaque material, such as sheet metal and preferably formed as a stamping out of a single piece. The general form of the visor is that of a quadrant of a hollow sphere, but by preference the base 22 occupies a plane below the plane of the light source (lamp 12).

The inner surface 23, by "silvering" or otherwise, is made highly reflective and at all points the reflective surface bears such angle with respect to the angle of the projected rays as to distribute the rays at relatively wide angles at both sides of the headlight and all such rays in a downward trend.

In the arrangement of the base 22 of the visor in a plane below the plane of the light source the objectional "glare" is prevented. By reason of the angle of the lens portion D with respect to the rays from the source the rays emanating from said portion D of the lens are all deflected downwardly, as indi-

cated at E in Fig. 1, and these same rays are deflected laterally by the curvature of the ribs 20 and 21 as indicated at F in Fig. 5. Obviously there will be straight ahead rays, 5 of great intensity and covering a relatively wide field, for "distance illumination."

As shown in Fig. 1 the angle of the lens portion C afforded by its concave curvature with respect to the light source deflects all 10 rays forwardly and upwardly, as indicated at G; and as indicated at H in Fig. 4 all such upwardly deflected rays are also deflected laterally by the prismatic ribs 17. All 15 the upwardly and laterally deflected rays emanating from the curved prismatic ribs are directed against the deflective surface of the visor and are thereby reflected downwardly.

The upper portion of the lens creates a more diffuse light than the lower portion 20 thereof because the prismatic ribs 17 throughout the upper portion of the lens break the light up to a greater extent than do the broader curved ribs, which are located in the lower portion of the lens. Hence 25 the most diffuse portion of the light delivered from the lamp is reflected downwardly by the visor B close to the front end of the automobile, while the less diffuse rays, which

are adapted to afford clearer illumination, are directed farther ahead on the roadway by 30 reason of passing below the lower edge of the visor.

I claim:

A headlight comprising a source of light, 35 a concave lens having upper and lower sections defined by a line, said upper section provided throughout with longitudinally curved prismatic ribs extending upwardly from said line operable to deflect rays upwardly and laterally, said lower section provided with ribs having concave surfaces and of greater width than said prismatic ribs, said ribs extending downwardly from said line and being longitudinally curved operable to deflect rays downwardly and laterally and a visor 40 in the form of a quadrant of a hollow sphere, positioned in front of the upper section of said lens to effect a downward and lateral deflection of all the light passing through said prismatic ribs said visor permitting an unobstructed forward passage for the rays of light passing through said broader concave ribs.

In testimony whereof, I have affixed my signature.

JACK CATHRILL.
